RADIATOR FOR MOTOR VEHICLES

Frederick C. Ruppel, Grand Rapids, Mich., assignor to W. B. Jarvis Company, Grand Rapids, Mich.

Application February 27, 1928. Serial No. 257,437

11 Claims. (Cl. 220—24)

The main object of this invention is to provide an improved radiator for automobiles in which an effective closure is provided for the filling opening and at the same time one which 5 may be quickly opened and is distinctive and attractive in appearance.

Objects pertaining to details and economies of my invention will definitely appear from the description to follow. The invention is defined 10 in the claims.

A structure embodying the features of my invention is clearly illustrated in the accompanying drawing forming a part of this application, in which:

15 Fig. 1 is a fragmentary view of my improved radiator partially in central vertical section.

Fig. 2 is a fragmentary view of a modified form of my invention partially in central vertical section.

20 In the accompanying drawing the radiator proper 1 is arranged within a shell 2. The radiator is provided with a filling neck 3 having an inwardly projecting flange 4 at its upper end providing a valve seat. The top of this neck is below the top 5 of the radiator shell which has an opening 6 therein above the filling opening of the radiator, affording access thereto. This opening preferably extends into the front 25 wall of the radiator shell at 7 so that free access is provided to the filling opening.

30 I provide a combined closure member and ornament 8 which in the preferred embodiment shown in Fig. 1 is hinged at 9 to the upwardly projecting ear 10 on the shell, the pivot being located at the rear of the opening. This closure is of a general angular form having a front flanged portion 11 overlapping and closing against the front wall 12 of the radiator.

35 On the front wall 12 is an upwardly curved spring latch 13, the flange part 14 of the closure having an opening 15 to receive this latch. The bottom edge 16 of the opening constitutes a keeper coacting with the latch to not only hold the closure in closed position but to exert a camming action, drawing the closure downward. The closure is designed as an ornament for the radiator, the particular closure illustrated representing a falcon or bird of prey.

40 The neck portion 81 serves as a handpiece for manipulating the closure. In closing it is only necessary to swing the closure downwardly and on a forward and upward pull the spring latch yields to permit opening. The closure member carries a valve or closure for the radia-

tor filling opening, this in the embodiment illustrated consisting of a supporting disk 17 mounted on the under side of the closure by means of the screw 18 and a hollow spherically curved valve member 19 formed of rubber, the edges 60 of the valve member being molded upon or otherwise secured to the edges of the supporting disk 17.

A hole 20 is provided in the bottom of the valve member to afford access to the head of the 65 screw 18.

With this arrangement an effective closure is provided, the valve member readily adapting itself to the valve seat around the filler opening and the necessity for great care in forming, assembling and alining the parts is not required. 70

In the modification shown in Fig. 2 the pivot ear 21 is supported in substantially the same relation relative to the radiator shell as the ear 10, but is carried by a ring 22 threaded upon 75 the neck of the radiator which is externally threaded to receive it.

In this embodiment a pivoted latch 23 is mounted at 24 on the depending portion of the closure member, the finger piece 25 of the latch 80 projecting forwardly therefrom. A keeper 26 is provided on the supporting ring 22. A spring 27 urges the latch to engaging position.

My improvements are readily adapted to different ornamental designs, that is, the ornamental design may be very considerably varied and still avoid upward projections breaking the general contour of the radiator. 85

I have illustrated and described my improvements in two practical embodiments. I have 90 not attempted to illustrate or describe other embodiments as I believe this disclosure will enable those skilled in the art to embody or adapt my improvements as may be desired.

Having thus described my invention what I 95 claim as new and desire to secure by Letters Patent is:

1. The combination with a radiator shell, of a radiator disposed therein and provided with a filling opening having an upwardly facing valve seat, said shell having an opening therein above said valve seat, a closure member hinged to said shell at the rear of said opening and having a downwardly projecting flange-like portion overlapping the front of the shell when the closure 100 is in closed position, a valve supporting disk mounted on the under side of said closure member, a hollow spherically curved valve member of resilient material having its edges engaged with the edges of said supporting disk and 110

- adapted to yieldingly coact with said valve seat when the closure member is closed, and an upwardly curved spring latch mounted on the front of said shell, said flange portion of said shell having an opening therein, the lower edge of which constitutes a keeper coacting with said latch. 5. The combination with a radiator shell, of a radiator disposed therein and provided with a filling opening having an upwardly facing valve seat, said shell having an opening therein above said valve seat, a closure member hinged to said shell at the rear of said opening and having a downwardly projecting flange-like portion overlapping the front of the shell when the closure is in closed position, a valve supporting disk mounted on the under side of said closure member, and a hollow spherically curved valve member of resilient material having its edges engaged with the edges of said supporting disk and adapted to yieldingly coact with said valve seat when the closure member is closed. 6. The combination with a radiator shell, of a radiator disposed therein and provided with a filling opening provided with an upwardly facing valve seat, said shell having an opening therein above said valve seat, a closure member hinged at the rear of said opening and having a downwardly projecting flange-like portion overlapping the front of the shell when the closure is in closed position, a valve supporting disk mounted on the under side of said closure member, a valve member of resilient material carried by said supporting disk and adapted to coact with said valve seat when the closure member is closed, and a spring latch mounted on the front of said shell, said flange portion of said closure member constituting a keeper coacting with said latch. 7. The combination with a radiator shell having an opening therein, a radiator having a filling opening aligned with said opening in said shell, an angled closure member hinged at the rear of said opening so that its vertical portion overlaps the front of the shell when the closure member is closed, a yielding valve carried by said closure member and adapted to coact with said valve seat when the closure member is closed, and a spring latch member coacting with said closure member to draw the same downwardly as the closure member is engaged therewith. 8. The combination with a radiator shell having an opening therein, a radiator having a filling opening aligned with said opening in said shell, an angled closure member hinged at the rear of said opening so that its vertical portion overlaps the front of the shell when the closure member is closed, and a yielding valve carried by said closure member and adapted to coact with said valve seat when the closure member is closed. 9. The combination with a radiator shell having an opening therein, of a radiator disposed therein and provided with a filling opening having a valve seat, a closure member pivotally mounted at the rear of said opening to swing forwardly and having a portion closing against the front side of the shell, a valve carried by said closure member and coacting with said filling opening seat when the closure member is in closed position, and a latch for retaining said closure member in closed position. 10. The combination with a radiator shell having a top wall with an opening therein, a radiator disposed within said shell and having a filling opening below the top wall and accessible through said opening in said shell, and a closure member mounted on said shell and provided with a closure for said filling opening when the closure member is in closed position. 11. The combination with a radiator shell having a top wall with an opening therein, a radiator disposed within said shell and having a filling opening below the top wall and accessible through said opening in said shell, a closure member for said opening in said shell adapted to lie in an approximately horizontal position when closed, and a valve for said filling opening carried by said closure member.

FREDERICK C. RUPPEL.
